UNITED STATES PATENT OFFICE.

LOUIS D. GREGG, OF HACKENSACK, NEW JERSEY.

RAIL FASTENING.

1,421,457.

Specification of Letters Patent.

Patented July 4, 1922.

Application filed October 20, 1921. Serial No. 509,039.

To all whom it may concern:

Be it known that I, LOUIS D. GREGG, a citizen of the United States, residing at Hackensack, county of Bergen, State of New Jersey, have invented new and useful Improvements in Rail Fastenings, of which the following is a specification.

This invention is an improvement upon the structure set forth by the Gregg Patent No. 638,922. The object of the present invention is to produce a rail-fastening which is applicable at will for securing rails whose flanges are of varying vertical dimensions or heights to cross-ties of varying configurations.

Among the features constituting the invention are: The longitudinal groove in the cross-ties is of rounded or arcuate cross-section, instead of straight-lined; the cross-tie has two holes for the two clips of each fastener, instead of having only one hole and locating the outer clip at the very end of the cross-tie; the clip-members are of malleable material, such as machine-forged steel, instead of being castings as heretofore; the upper surface of the lower jaw of the clip is concaved and rounded, instead of being flat; the upper jaw of the clip extends substantially horizontally from the vertical portion thereof at substantially a right angle or less, instead of sloping upwardly; and the inside-clearance of the vertical portion of the clip is increased to exceed the vertical distance between the lower bearing-surface of the tie and the outer upper edge of the rail-flange. The invention likewise comprises the various combinations of the above-mentioned features; and the other features hereinafter set forth and claimed.

The broad invention will be best understood by reference to a preferred concrete embodiment of all the various features thereof illustrated in the accompanying drawings, in which:

Fig. 1 shows, in plan, the end-portion of the new cross-tie and a portion of a rail secured thereto by the new fastening-device;

Fig. 2 is a vertical section through the line 2—2 of Fig. 1;

Fig. 3 is a vertical section through the line 3—3 of Fig. 1;

Fig. 4 is a plan, similar to Fig. 1, but with the rail and fastening-device entirely removed;

Fig. 5 is a vertical section, similar to Fig. 2, but showing the end of a modified form of rail; and

Fig. 6 is a vertical section similar to Fig. 3, but showing a different form of cross-tie and a rail like that of Fig. 5.

Referring first to Figs. 1—4, 10 represents a cross-tie whose central longitudinal portion is depressed in curved or arcuate form, as at 12, to produce on its upper surface a longitudinal groove. 13 is a hole through said grooved portion for receiving one of the two fastening-clips; 14 is a larger opening nearer the end of the tie, for receiving the complementary clip and for manipulating the nut of a bolt; and 15 is the intermediate depressed portion of the tie. 16 is a rail, resting in position on the tie and lying above said depressed portion 15, between said hole and opening, and having the usual base-flanges 17—17 with inclined upper surfaces. 18 and 18' are a pair of identical but oppositely-disposed clip-members, each having a central bolt-hole. Preferably, the height of the inner face 19 of the vertical portion of each clip, its vertical inner-clearance, exceeds the vertical distance between the bottom bearing-surface of the tie-depression 15 and the upper and outer edge 20 of said flanges. Each clip has a substantially-horizontal upper jaw 21, which extends from said vertical face 19 at approximately a right angle or preferably even less. Said vertical face 19 and the bottom face of said jaw 21 may be substantially-plane surfaces; but each clip has likewise a lower jaw 22, which is arcuate (when viewed in a direction transverse to the rail, as in Fig. 3) to present a concaved upper surface.

When a rail as 16 is laid in place above tie-portion 15, intermediate hole 13 and opening 14, the pair of clips, 18 and 18', is applied to the rail-flanges and a bolt 23 inserted first through inner clip 18' and then through outer clip 18, and if desired the head of the bolt may be turned to engage the wall of the groove to prevent rotation; and then a nut 24 is screwed home upon said bolt to draw said clips towards one another and clamp them upon the rail-flanges and tie-depression.

As stated, preferably the vertical extent of said inner face 19, the vertical inside clearance of the clip, slightly exceeds the

vertical distance between the engaged surface of the tie-depression 15 and the upper outer edge of the superposed rail-flanges; so that, when the clips and their bolt have been located in position and the nut screwed home on its bolt, the outer edge of each upper jaw will pass over said upper outer edge of the adjacent rail-flange, and will engage the inclined flange-surface along a line about midway of the flange. With a relatively-thick flange, as 17' in Fig. 5, said engagement will be nearer the outer edge. And with a relatively-thin flange, the engagement will be nearer the rail; and, if necessary or desired, the upper clip-jaws can be forced downward, as by hammering, either before or after assembling, to insure proper engagement. In either event, the tightening-up of the nut, with or without the hammering, will produce a wedging and clamping action to maintain a firm engagement of the flanges and secure the rail in place. The fact that the clips are malleable is therefore of great advantage, in enabling the new fastener to be applied to rails of the different types.

In Fig. 5 is indicated a rail 16' having relatively-thicker flanges 17' with the usual inclined upper surfaces. With such rails, the upper jaws 21 need not be hammered down, but will engage said inclined surfaces nearer the outer edges than with the thinner rail-flanges shown in Fig. 2.

In Fig. 6 the central tie-depression 15', which constitutes the longitudinal groove, is rounded upon a radius substantially shorter than that of depression 15 in Fig. 3; so that the lower clip-jaws 22 engage along the central portion of the under surface of said shorter-radius depression, as clearly indicated in Fig. 6; whereas a longer-radius depression is engaged along two separate lines or regions nearer the outer edges of the jaw, as indicated in Fig. 3.

The invention has thus been described with considerable detail, but only for the sake of clearness; since it is to be understood that the invention is not limited to the precise construction and arrangement set forth, but may be embodied in various forms, and parts of the invention may be omitted, without departing from the spirit of the broad invention.

The invention having thus been described, what is claimed is:

1. The combination of a cross-tie having a rounded longitudinal depression, and having two holes, a rail in position upon said tie with its flanges located between said holes, two complementary apertured clips of malleable metal located one in each of said holes and each having two jaws and a vertical portion whose inside vertical-clearance exceeds the distance between the bottom bearing-surface of said depression and the upper

outer edge of said superposed flanges, each of said upper jaws extending from said vertical portion at not greater than a right angle and engaging upon the upper surface of its adjacent rail-flange, each lower jaw having a concave upper face engaging the lower surface of said depression, a bolt passing through said apertures in said clips and having a head engaging one clip, and a nut screwed on said bolt to clamp said clips towards one another and upon the flanges and tie respectively.

2. The combination of a cross-tie having a rounded longitudinal depression and a hole therethrough, a flanged rail in position upon said tie between said hole and the end of said tie, two complementary apertured clips of malleable metal, one of them located in said hole, said clips having two jaws and a vertical portion whose inside vertical-clearance exceeds the distance between the bottom bearing-surface of said depression and the upper outer edge of the superposed rail-flanges, each of said upper jaws extending from said vertical portion at not greater than a right angle and engaging upon the upper surface of its adjacent rail-flange, each lower jaw having a concave upper face engaging the lower surface of said depression, a bolt passing through said clips and having a head engaging one clip, and a nut screwed on said bolt and engaging the other clip to draw said clips towards one another and clamp the flanges upon the tie.

3. The combination of a cross-tie having a hole therethrough, a flanged rail in position upon said tie between said hole and the end of said tie, two complementary apertured clips of malleable metal, one of them located in said hole, each of said clips having two jaws and a vertical portion whose inside vertical-clearance exceeds the distance between the bottom bearing-surface of said tie and the upper outer edge of the superposed rail-flanges, each of said upper jaws extending from said vertical portion at not greater than a right angle and engaging upon the upper surface of its adjacent rail-flange, each lower jaw engaging the lower surface of said tie, a bolt passing through said clips and having a head engaging one clip, and a nut screwed on said bolt and engaging the other clip to draw said clips towards one another and clamp the flanges upon the tie.

4. The combination of a cross-tie having two holes, a rail in position upon said tie with its flanges located between said holes, two complementary apertured clips located one in each of said holes and each having two jaws and a vertical portion whose inside vertical-clearance exceeds the distance between the bottom bearing-surface of said tie and the upper outer edge of said superposed flanges, each of said upper jaws extending from said vertical portion at not

- greater than a right angle and engaging upon the upper surface of its adjacent rail-flange, each lower jaw engaging the lower surface of said tie, a bolt passing through 5 said apertures in said clips and having a head engaging one clip, and a nut screwed on said bolt to clamp said clips toward one another and upon the flanges and tie respectively.
- 10 5. A fastening-device for securing a flanged rail upon a cross-tie, comprising two similar but oppositely-disposed apertured clips of malleable material each having two jaws adapted to engage respectively the under surface of said tie and the inclined 15 upper surface of the adjacent rail-flange, the inner face of the vertical portion of each clip being of greater height than the distance between said bottom bearing-surface of the tie and the outer upper edge of the rail-flanges, 20 said upper jaw extending at less than a right-angle from said vertical inner face, a headed bolt passed through said apertures in said clips, and a nut screwed upon said bolt to draw said clips together under tension and clamp said flanges upon said ties.

LOUIS D. GREGG.
